(57) **CLAIM**

The ornamental design for a vehicle mounted expandable mobile building, as shown and described.

DESCRIPTION

FIG. 1 is a top, front and left side perspective view of the vehicle mounted expandable mobile building embodying my new design.

FIG. 2 is a top, rear and left side perspective view of the vehicle mounted expandable mobile building.

FIG. 3 is a bottom, front and left side perspective view of the vehicle mounted expandable mobile building.

FIG. 4 is a front elevation view of the vehicle mounted expandable mobile building.

FIG. 5 is a rear elevation view of the vehicle mounted expandable mobile building.

FIG. 6 is a left side elevation view of the vehicle mounted expandable mobile building.

FIG. 7 is a top, front and left side perspective view of the vehicle mounted expandable mobile building when in a closed position.

FIG. 8 is a top, rear and left side perspective view of the vehicle mounted expandable mobile building when in a closed position.

FIG. 9 is a bottom, front and left side perspective view of the vehicle mounted expandable mobile building when in a closed position.

FIG. 10 is a front elevation view of the vehicle mounted expandable mobile building when in a closed position.

FIG. 11 is a rear elevation view of the vehicle mounted expandable mobile building when in a closed position.

FIG. 12 is a right side elevation view of the vehicle mounted expandable mobile building when in a closed position; and, FIG. 13 is a top plan view of the vehicle mounted expandable mobile building when in a closed position.

Features shown in broken lines are provided for the purposes of illustrating environmental structure and form no part of the claimed design.
